(57) CLAIM

The ornamental design for a fence, as shown and described.

DESCRIPTION

FIG. 1 is a front perspective view of a fence, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is front perspective view of the fence shown in an environment of use.

The broken lines shown in the drawings depict portions of the fence, that form no part of the claimed design.
